UNDERREAMER

Herman C. Smith, Whittier, Calif.

Application May 29, 1936, Serial No. 82,483

7 Claims. (Cl. 255—75)

This invention relates to underreamers, and particularly to that class of underreamers operated by rotary apparatus.

The use of underreamers in the oil well industry is well understood, particularly where formation is to be cut a size larger than the drilling tool. The necessity for enlarging a well hole results where it is desired to cement back of a casing and also where casing shoes are used which are, of necessity, larger than the drill.

An object of the present invention is to provide an underreamer wherein cutter members are out of casing engagement while the underreamer is being lowered through a casing, and then moved into formation engagement at the will of the operator, the operative control being at the surface of the well hole.

Another object is the provision of an hydraulically controlled underreamer, the hydraulic control being such as to actuate positive mechanical means in turn directing cutter members of said underreamer into formation engagement.

Another object is the provision of an underreamer which may have the cutter elements thereof controlled from the surface of the well, hydraulically, and in such a manner that the diameter of the reamed hole may be varied.

Another object is the provision of an underreamer having few parts, simple of construction, positive in operation, which may be readily assembled and disassembled, which permits any broken parts to be easily removed, and is generally superior to underreamers now known by the inventor.

Another object is the provision of an underreamer not dependent for operation upon the use of springs for expanding cutters.

Another object is the provision of an underreamer which may be readily passed through a casing without the cutters injuring the casing or in turn the casing injuring the cutters.

Other objects and uses of the invention will readily suggest themselves to those skilled in the art, and with the above set forth objects, including simplicity of structure, inexpensiveness in cost of manufacture, in view, the invention consists in the novel and useful provision, formation, construction, association, and relative arrangement of parts, members and features, all as shown in a certain embodiment in the accompanying drawings, described generally, and more particularly pointed out in the claims.

In the drawings:

Figure 1 is a fragmentary sectional view of a well hole within which is received the improved

underreamer, the underreamer cutters being in formation engagement below the well casing.

Figure 2 is an enlarged fragmentary vertical sectional view of the underreamer within well casing.

Figure 3 is an enlarged fragmentary vertical sectional view, the underreamer cutters being below the lowermost end of the casing and in formation engagement, and,

Figures 4, 5, 6 and 7 are sectional views on the lines 4—4, 5—5, 6—6, and 7—7 of Figure 2, respectively.

Referring now to the drawings, 1 is the underreamer as an entirety, and the same includes a body 2 provided with a central bore 3, both ends of the body being reduced as to external diameter, as indicated at 4 and 5, the end 4 being formed with a pin, indicated in dotted lines in Figure 1 at 6, and the opposite end 5 being formed with a threaded box shown in dotted lines at 7. In the present instance, the body is provided with longitudinally extending peripheral grooves, channels or troughs 8, three grooves, channels or troughs equidistantly spaced apart being provided for the present underreamer, as best illustrated in Figures 4 to 7, inclusive. Each groove is so formed that a cross section through the body defines a curved bounding wall. This curvature is necessary in order that certain other elements of the invention, to-wit, the cutters, may be confined within the groove or grooves. Arcuate end walls 9 and 10 form the termini for each groove 8.

As all the grooves 8 are identical in construction, and the mechanism for placement within the grooves is likewise identical, only one groove with its mechanism will be described, the same numerals of reference applying in each case.

Referring more particularly to Figures 2 and 3, a series of cutter rollers 11, 12 and 13 are mounted upon a shaft 14. The cutter rollers may progressively vary as to external and internal diameter; for instance, in the present case, the cutter roller 11 is of lesser external and internal diameter than the roller 12 or 13, and the same is true for the roller 12 with respect to the roller 13. The shaft 14 is formed with eccentric step portions 15 and 16 to accommodate the rollers 12 and 13. The eccentricity of the portions 15 and 16 is with respect to the axis of the portion 17 of the shaft. Forming an extension of the shaft 14 is a threaded shank 18, the axis of which lies in the axis of the portion 17 of the shaft. The threads are of the double square type and the helical angle is preferably at a degree 55

adapted to rapidly turn the shaft when the said threads engage internal threads of a member to be described. In the present instance, the helical angle of the threads is substantially 45°. The 5 threads of this shank cooperate with member 19, which is internally provided with double square threads 20. The member 19 co-operates with member 21. This member has one face 22 thereof curved to accommodate the same within the 10 curved portion 9 of the groove, and when so positioned, may be secured to the body by spot welding or by other suitable means, as shown at 23. The member 21 is under-cut at 24, and the member 19 is provided with a lug or tongue 25 15 adapted to fit between the wall bounding the groove 8 and within the under-cut portion 24 of the member 21. The member 21 is provided with a transverse bore 26 and the lug 25 is formed with a threaded bore 27, which said bores are in 20 alignment when the members 19 and 21 are co-operating, as shown in Figures 2 and 3. A screw 28 may be passed through the bore 26 and have threaded engagement with the threaded bore 27. Thus, the two members are held in locked 25 engagement. Reference to Figure 4 shows that side thrust of the members 19 and 21 is effectively resisted by the said members closely engaging the wall bounding the groove 8.

The portion 17 of the shaft 14 is threaded at 29, 30 and a sleeve 30 in part surrounds the part 17 of the shaft 14 and is threaded at 31 for engagement with the threads 29. The said sleeve which forms what will be termed a piston is fitted within a bore 32 of a block 33. This block carries at one end 35 a tongue or lug 34 adapted to be received within a cut-away portion 35 of a member 36. This member is similar in construction to the member 21, in that it is provided with a transverse bore 37, which is adapted to align with a threaded bore 40 38 in the bore 35, whereby a threaded screw 39 may be passed through said bore 35 for threaded engagement with the threads 38. This block 36 is conveniently held to the portion 10 by welding, as indicated at 40. The member 33 is provided with 45 a transverse bore 41, which is adapted to communicate with a port or bore 42 formed in the body 8 and opening within the central bore 3 of the body.

For convenience of description, the members 21 50 and 36 may be hereinafter designated as end supports. The block 33, termed a cylinder, and the block 19 together with the screw shank 18, is mechanical means for rotating the shaft when the shaft is moved in one direction.

55 The operation, uses and advantages of the invention just described are as follows:

I assume, of course, that the present underreamer is provided with three equidistantly spaced-apart sets of roller cutters so that there 60 is a normal balance without undue side movement when the underreamer is in actual use. The cutters are in the position shown in Figures 1 and 2 when the underreamer is passing through 65 the well casing 43. It will be observed that the peripheries of the cutter teeth are out of engagement with the inner surface of the casing. The cutters are supported one upon the other, the lowermost cutter 11 having its base resting upon 70 the upper end of the sleeve 30 and a portion of the block 33. This position is maintained due to the fact that the portion 16 of the shaft carries an integrally formed or otherwise secured flange 44 which bears against the top of the uppermost cutter 13. It is intended that the cutters 11, 12 75

and 13 should rotate freely upon their respective shaft portions 14, 15 and 16.

The underreamer may be conveniently lowered within the well hole by providing the usual box coupling 45, the pin 6 of the underreamer being secured within one box, and the lower end of drill pipe 46 secured to the other box. As usual, a bit of some character, such as the fishtail shown at 47, may have the pin thereof received within the threaded box 7 of the underreamer. The underreamer cutters are held collapsed within the different grooves until the cutters are below the lowermost end of the casing 43. If hydraulic pressure or flow of mud under pressure is maintained through the drill string and the underreamer outwardly through the openings 48 of the fishtail bit, a portion of said mud under pressure will enter the ports 42 into the bores 41 and exert a pressure against the pistons which, as before stated, includes the lower end of the shaft 14 where it is in threaded engagement with the sleeve 30. This pressure will force the pistons upwardly within the bores 32, forming the cylinders of the blocks 33, and in so doing, the external threads 18 will travel within the internal threads 29 of the members 19, resulting in a turning of the shafts 14. As the portions 15 and 16 of the shaft are eccentric to the portion 14, the cutter rollers will be moved into engagement with the formation below the end of the casing, in the manner illustrated in Figure 3. Furthermore, the cutting will be in stages; for instance, the cutter 11 will not engage the formation as deeply as the following cutter 12, and the same is true with respect to the cutter 13. This renders cutting 35 easier and more positive, with less likelihood of the underreaming operation resulting in a crooked hole. It is evident that the degree of pressure maintained within the drill string and outwardly of the bit 47 will directly control the 40 pressure engagement of the cutter rollers against the formation until open or fully expanded. Hence, the operator at the surface of the well hole may determine by the action of the rotary table during rotation of the drill string and the 45 reamer, the degree of cut required.

When it is desired to withdraw the underreamer from the well hole, pressure may be relieved through the drill string which will, of course, relieve pressure from within the cylinder portion of the block 33, with the result that when the tapered end teeth of the cutter roller 13 engage the lowermost portion of the casing, the shaft 14 will be rotated by the threads 18 moving relative to the internal threads 29 of the block 50 19 until such time that the cutter may move within the confines of the casing, which will substantially be the position for all of the cutters depicted in Figure 2.

I claim:

1. An underreamer including an annular body formed with a peripheral groove, a cutter, and a shaft having threaded engagement with the body and eccentrically carrying said cutter and normally maintaining the cutter within the confines of said groove, and hydraulically operated means for moving the shaft longitudinally and rotating the same by reason of its threaded engagement with the body to project said cutter outwardly from said groove.

2. An underreamer including a body having a curved periphery and a central bore and provided with a longitudinally extending groove opening inwardly of the periphery thereof, a roller cutter, and means in threaded engagement with the

body for eccentrically mounting said cutter for confinement within said groove and for movement outwardly of said groove and beyond the periphery of the body, and hydraulic means for 5 the first means to rotate the same by reason of its threaded engagement with the body to project said cutter outwardly of the groove.

3. In underreamer construction, an elongated body provided with a curved periphery and with 10 a central water course, a shaft carried by the body and defining at one end a piston, a cylinder in communication with the water course of the body and receiving the piston end of the shaft, and means for said shaft to positively turn the 15 same when the piston is moved within the cylinder.

4. In underreamer construction, an elongated body provided with a curved periphery and with a central water course, said body provided with 20 an elongated groove, a shaft carried by the body and defining at one end a piston, a cylinder in communication with the water course of the body and receiving the piston end of the shaft, means for said shaft to positively turn the same when 25 the piston is moved within the cylinder, and a cutter roller within said groove and eccentrically carried on the shaft, whereby the cutter roller is moved outwardly of and inwardly of the groove when the shaft is rotated.

30 5. An underreamer including a body provided with a central water course, and provided with a peripheral groove, a cutter roller, and a shaft for eccentrically mounting said roller, said shaft provided with a piston portion, a cylinder member 35 in communication with the water course and receiving one end of said piston, and a screw shank secured to said shaft, a block provided with internal threads for engagement with said screw shank, said block being secured to the said body 40 whereby when fluid is passed through said water

course into said cylinder, the piston is moved in one direction and rotated, the said cutter roller being moved outwardly from said groove beyond the periphery of the body.

6. An underreamer including a body provided with a substantially curved periphery and with a central water course, a block, provided with internal screw-threads, secured to said body within the said groove; a cylinder member within said groove, a shaft provided at one end with screw-threads for threaded engagement with the threads of the block, said shaft provided at the other end with a piston portion received within said cylinder, and a cutter roller eccentrically mounted upon said shaft, the relationship being 15 such that fluid passed through said water course and admitted into said cylinder will actuate the piston in one direction to rotate said shaft through the threaded arrangement to in turn move the cutter roller outwardly of said groove. 20

7. An underreamer including a body provided with a substantially curved periphery and with a central water course, a block, provided with internal screw-threads, detachably secured to said body within the said groove; a cylinder member 25 within said groove, and means for detachably securing said member to said body, a shaft provided at one end with screw-threads for threaded engagement with the threads of the block, said shaft provided at the other end with a piston 30 portion received within said cylinder, and a cutter roller eccentrically mounted upon said shaft, the relationship being such that fluid passed through said water course and admitted into said cylinder will actuate the piston in one direction 35 to rotate said shaft through the threaded arrangement to in turn move the cutter roller outwardly of said groove.

HERMAN C. SMITH. 40
